UNITED STATES PATENT OFFICE.

ROBERT R. HUGHES, JR., OF UTICA, NEW YORK, ASSIGNOR TO UNION SPECIAL MACHINE COMPANY, OF CHICAGO, ILLINOIS, A CORPORATION OF ILLINOIS.

MACHINE FOR FORMING CONCEALED STITCHES.

Application filed December 30, 1920. Serial No. 434,012.

To all whom it may concern:

Be it known that I, ROBERT R. HUGHES, Jr., a citizen of the United States, residing at Utica, in the county of Oneida, State of New York, have invented certain new and useful Improvements in Machines for Forming Concealed Stitches, of which the following is a description, reference being had to the accompanying drawing and to the figures 10 of reference marked thereon.

The invention relates to new and useful improvements in sewing machines for forming concealed stitches which do not show on the right or face side of the material being stitched. In my copending application Serial No. 310,073, filed July 11, 1919, I have shown a machine for forming stitches of the above character, and the present machine is an improvement upon the machine set forth 20 in said application.

An object of the present invention is to provide a machine of the above character, wherein the needle is so disposed as to penetrate the binding strip at a point within and 25 at or very close to the folded edge so as to hold the binding strip tightly about the edge of the fabric being bound.

Another object of the invention is to provide a support for a sewing machine of the above character, whereby the machine during stitching is held thereon with the work support inclined upwardly from front to rear so as to facilitate the directing of the material being stitched.

35 A further object of the invention is to provide a machine of the above type with bearings for the needle bar wherein the upper bearing is extended to form a housing for the upper end of the needle bar during its reciprocation.

40 A still further object of the invention is to provide a machine of the above character with a presser foot arranged wholly in rear of the folder and needle and having a curved guiding section for the binding strip at the front end thereof.

These and other objects will in part be obvious and will in part be hereinafter more fully disclosed.

50 In the drawings, which show by way of illustration one embodiment of the invention:—

Figure 1 is a view of the left hand end of a machine embodying my improvements;

55 Fig. 2 is a view of the right hand end of

the machine with the cover plate for certain of the vibrating parts removed;

Fig. 3 is a view from the front of the machine, the latter being removed from its inclined support;

Fig. 4 is a plan view of the machine;

Fig. 5 is a plan view of the parts located beneath the work support;

Fig. 6 is a sectional view longitudinally through the needle bar bracket;

Fig. 7 is a sectional view on the line 7—7 of Fig. 9, also showing the needle;

Fig. 8 is a vertical sectional view through the folder substantially in the line of feed;

Fig. 9 is a perspective view showing a body fabric having the binding attached thereto and showing the manner of leading and folding the binding;

Fig. 10 is a sectional view on the line 10—10 of Fig. 9;

Fig. 11 is a side view of the presser foot;

Fig. 12 is a plan view of the presser foot showing the presser bar in section.

In my prior application above referred to, I have disclosed a sewing machine for forming concealed stitches wherein the needle reciprocates in a line at an obtuse angle to the plane of the work support. The binding strip is directed to the needle by means

80 of a folder or guide which is so constructed as to fold the upper edge of the binding strip about the path of the needle as it is led to the point where the needle penetrates the materials, and at the penetrating point the inturned edge of the upper portion 85 of the binding strip is directed across the needle path so that the needle penetrates said inturned edge and the body fabric. One of the features of the present invention consists in setting the needle so that it reciprocates in a line, not only at an obtuse angle to the plane of the work support, but at a slight angle to a vertical plane containing the line of feed. This aids materially 90 in the placing of the needle so that it will penetrate the inturned part of the upper portion of the binding at or very close to the folded edge, and thus secure the binding tightly about the edge of the body fabric.

95 In order to provide a right angle driving connection between the needle bar and the upper rock shaft, I have positioned said shaft at a slight angle to a vertical plane containing the main shaft.

100 In a machine of the above type where the

110

needle reciprocates in a line at an obtuse angle to the plane of the work support and the binding strip is directed so that the in-turned portion surrounds the needle path, the body fabric, in order to be bound, must be led to the stitching point in the same general direction as the path of reciprocation of the needle. In order to facilitate the handling of the material, I have provided a supporting base for the sewing machine which is so constructed that the entire machine is tilted, thus bringing the work support to a position inclined upwardly to the horizontal from front to rear. The presser foot is arranged entirely in rear of the needle path so as to permit the free passage of the body fabric while within the binding strip which in turn is folded about the path of the needle, and the front end of the foot is shaped so as to aid in the guiding of the binding strip after it leaves the folder.

The invention may possibly be made more clear by a detailed reference to the drawings, wherein I have shown my improved machine as consisting of a bed plate 1 carrying a work support 2 and a standard 3 having an overhanging arm 4. The bed plate 1 is supported by a block 5 having an inclined upper face 6 so that the work support 2 is inclined upwardly to the horizontal from front to rear, and this greatly facilitates the directing of the material through the machine, as will appear more fully hereinafter.

The needle of the stitching mechanism is indicated at 7. Said needle is carried by a needle bar 8, and the needle bar 8 reciprocates in bearings 9 and 10 carried by a bracket 11. The bracket 11 is formed with an extension 12 which extends the full length of the overhanging arm 4. At the rear end of this extension 4 there is provided a depending part 13. A screw 14 passing through the bracket is threaded into the standard 3 and serves as a means for securing the right hand end of the bracket. The left hand end of the bracket is secured rigidly to the lugs 15 and 16.

The needle bar is reciprocated by means of a forwardly extending arm or lever 17 which is rigidly secured to the outer end of a rock shaft 18. This shaft 18 is mounted for oscillation in bearings 19 and 20 formed in the bracket. It will be apparent from Figs. 4 and 5 of the drawings that this shaft 18 has its axis set at a slight inclination to the normal plane of the overhanging arm 4, and also to a plane containing the main operating shaft 21. As also shown in Fig. 4, the oscillating lever or arm 17 and the path of reciprocation of the needle bar lie in a plane at right angles to the axis of this shaft 18 and, consequently, in a plane cutting a vertical plane containing the line of feed slightly at an angle.

The shaft 18 is oscillated by means of a rearwardly extending arm 22 which is rigidly secured to the rear end of the shaft. On the end of the main shaft 21 there is a belt wheel 23 having a crank pin 24. A link 25 is connected to this crank pin and to a ball stud 26 at the outer end of the arm 22. The main shaft 21 rotates to oscillate the arm 22, which in turn operates the shaft 18, and this shaft oscillates the needle lever or arm 17 which reciprocates the needle bar. The load and the driving mechanism therefor are thus distributed on opposite sides of the shaft 18. As above noted, this needle bar reciprocates in a line which cuts the plane of the work support at an obtuse angle. In the present illustration of the invention this angle is approximately 135°.

The material is fed across the work support by means of a feed dog 27. Said feed dog is carried by a feed bar 28 which is reciprocated by means of an arm 29 cooperating with a crank on the end of the main shaft 21 in the usual manner. The feed bar is also raised and lowered in the usual manner. The feed bar and feed dog have the usual relation to the work support, and feed the material in a direction across the work support, parallel with the end of the work support and at right angles to the front and rear edges of the work support.

Cooperating with the needle 7 beneath the work support is a threaded looper 30. Said looper is mounted on a looper carrier 31, and said looper carrier is in turn pivoted to a looper rocker 32 carrying a sleeve 33 oscillated by means from the main shaft 21, and thus give to the looper its needle avoiding movement. The looper carrier is oscillated by means of a link 34 which is pivoted at its rear end to a stud 35 carried by one arm of a rock lever 36. This rock lever 36 is pivoted at 37 to the depending portion 13 of the bracket 11. The other arm of the rock lever 36 is pivoted at 38 to a link 39, and this link 39 is in turn pivoted to the arm 22 at 40, see Fig. 2. The arm 22 is oscillated from the main shaft, and as it oscillates the link 39 will oscillate the rock lever 36 and this will oscillate the looper.

In Figs. 7 to 10 of the drawings, I have shown the body fabric F to which a binding strip B is attached. The binding strip is folded intermediate its edges about the path of movement of the body fabric and about the path of the needle, as clearly shown in Fig. 7. The upper edge portion of the binding strip is turned underneath the path of reciprocation of the needle 7, and the needle 7 penetrates this inturned portion of the upper part of the binding strip and forms stitches which are indicated diagrammatically at S in Fig. 7. In Fig.

10 I have shown a section through the binding strip and body fabric. It will be noted that the stitches S pass through the binding strip very close to the fold b therein on the upper face of the goods, and also through the binding strip on the under face of the goods. As the stitches pass through the binding strip at the folded edge, the binding will be held very tight about the edge 10 of the body fabric.

As a means for guiding the binding strip, I use a folder having a supporting base 41 which carries a flat plate 42, and mounted on this flat plate 42 is a folder consisting 15 of a guiding body portion 43 and a scroll 44 adapted to receive the reversed strip and inturn the upper edge portion thereof. The folder per se forms no part of the present invention, and further detailed description 20 thereof is not thought necessary. The essential features of the folder consist in the leading of the binding strip in a direction at substantially right angles to the path of travel of the strip as it is stitched to the 25 body fabric the folding of the binding strip intermediate its edges, and reversing the same so that said strip is folded about the path of reciprocation of the needle and the path of travel of the main body fabric. 30 The folder is also provided with means for inturning the upper edge portion of the binding strip so as to direct it underneath the needle and across the path of the needle at the point where the needle penetrates 35 the body fabric so that the upper inturned portion crosses the needle path with the body fabric and will be stitched to the body fabric. The inclining of the needle path to the plane of the work support and line 40 of feed enables the point of the needle to enter the inturned part of the binding strip at a point at or very near the edge of the binding strip and thus form a tight binding about the edge of the material, as above 45 described. It will be noted that the end 8^a of the needle bar is tapered which permits the reciprocation of the needle bar without the end of the needle bar striking the material being directed to the stitching mechanism.

The presser foot, indicated at 46 in the drawings, is carried by a presser bar 47 and is provided with a yielding section 48 normally forced downwardly by a spring 49. 55 The needle enters the material in front of the presser foot. The rigid portion 50 of the presser foot is provided with a cut-away section 51 which aids in guiding the binding strip and directing it so that the 60 folded edge will be held close to the path of the needle as the needle penetrates the inturned part of the upper portion of the binding strip.

The needle bar 8 extends through a sleeve

52, and this sleeve 52 is provided with lugs 65 with which a link 53 connects, and this link in turn is connected to the arm or lever 17. A set-screw 54, having an enlarged knurled head readily accessible to the operator, serves as a means for securing the needle 70 bar to the sleeve 52. By turning the set-screw 54, the needle bar may be quickly released from the sleeve 52, and the needle bar raised to a higher position than it can be raised by the normal operating mechanism, and this greatly facilitates the directing of the material through the binder and the removal of the binder from the machine, if desired, and more particularly aids in 75 positioning the needle for ready threading. 80

A screw 55 threaded into the needle bar engages a slot 56 in the sleeve 52 and holds the needle bar from turning. The bearing 9 is slotted, as indicated at 57 in Fig. 3. Extending through the upper end of the needle bar is a tube 58 which is held in place by a set-screw 59. This tube extends out through the slot 57, there being a slot at 85 each side of the bearing, and the tube reciprocates up and down in the slot with the needle bar. The needle thread is led from the supply through a suitable eye 60, thence through a tension 61, thence through a guide eye 62 to a guide eye 63 carried by the oscillating lever or arm 17, then through a guiding eye 64, thence through the tube 58 to a tension plate 65, and thence through a 90 guide slot 66 formed in the bearing 10 to the eye of the needle. 95

Inasmuch as the needle bar projects forward toward the operator, it is desirable to completely house the needle bar during its reciprocation. This is accomplished by extending the bearing 9 to a point above the extreme upper position of the needle bar, 100 and the tube and slot construction provides a ready means for guiding the thread by the upper end of the needle bar, although said upper end of the needle bar is housed completely during its reciprocation. 105

It is obvious that minor changes in the details of construction and the arrangement of the parts may be made without departing from the spirit of the invention as set forth in the appended claims. 115

Having thus described the invention, what is claimed as new is:

1. A sewing machine including in combination, a work support, a feeding mechanism, a stitching mechanism having a needle located in a line at an obtuse angle to the plane of the work support and in a plane cutting a vertical plane containing the line of feed at a slight angle, a folder for guiding a binding strip and having means for folding the upper edge portion thereof about the path of the needle and for directing said inturned folded portion across the 120 125

path of the needle, said needle being disposed so as to penetrate the binding strip at the fold in the upper edge portion thereof.

2. A sewing machine including in combination, a work support, a feeding mechanism, a stitching mechanism having a needle located in a line at an obtuse angle to the plane of the work support and in a plane cutting a vertical plane containing the line of feed at a slight angle, a folder for guiding a binding strip and having means for folding the upper edge portion thereof about the path of the needle for directing said inturned folded portion across the path of the needle, said needle being disposed so as to penetrate the binding strip at the fold in the upper edge portion thereof, said stitch forming mechanism including a rock shaft disposed in a line cutting said plane containing the needle at right angles.

3. A sewing machine including in combination, a work support; a feeding mechanism, a stitching mechanism having a needle located in a line at an obtuse angle to the plane of the work support and in a plane cutting a vertical plane containing the line of feed at a slight angle, a folder for guiding a binding strip and having means for folding the upper edge portion thereof about the path of the needle for directing said inturned folded portion across the path of the needle, said needle being disposed so as to penetrate the binding strip at the fold in the upper edge portion thereof, said stitch forming mechanism including a rock shaft disposed in a line cutting said plane containing the needle at right angles, an arm rigidly carried by the rock shaft, a needle bar carrying said needle, and a link connecting the arm to said needle bar.

4. A sewing machine including in combination, a work support, a feeding mechanism, a stitching mechanism having a needle located in a line at an obtuse angle to the plane of the work support and in a plane cutting a vertical plane containing the line of feed at a slight angle, a folder for guiding a binding strip and having means for folding the upper edge portion thereof about the path of the needle for directing said inturned folded portion across the path of the needle, said needle being disposed so as to penetrate the binding strip at the fold in the upper edge portion thereof, said stitch forming mechanism including a rock shaft disposed in a line cutting said plane containing the needle at right angles, an arm carried by the rock shaft, a needle bar, a sleeve surrounding the needle bar, means for rigidly and detachably connecting the sleeve to the needle bar, and a link connecting the arm to said sleeve.

5. A sewing machine including in combination, a work support, a feeding mechanism, a stitching mechanism having a

needle located in a line at an obtuse angle to the plane of the work support and in a plane cutting a vertical plane containing the line of feed at a slight angle, a folder for guiding a binding strip and having means for folding the upper edge portion thereof about the path of the needle for directing said inturned folded portion across the path of the needle, said needle being disposed so as to penetrate the binding strip at the fold in the upper edge portion thereof, said stitch forming mechanism including a rock shaft disposed in a line cutting said plane containing the needle at right angles, an arm carried by the rock shaft, a needle bar, a sleeve surrounding the needle bar, means for rigidly and detachably connecting the sleeve to the needle bar, a link connecting the arm to said sleeve, said sleeve having a slot therein, and a screw threaded into the needle bar and disposed in said slot for preventing the needle bar from turning when released from connection with said sleeve.

6. A sewing machine including in combination, a work support, a feeding mechanism, a needle, a needle bar carrying said needle, said needle bar being located in a line forming an obtuse angle to the plane of the work support, an oscillating arm for reciprocating said needle bar, a sleeve surrounding the needle bar, a link connecting said sleeve to said arm, and a set-screw for rigidly and detachably connecting the needle bar to said sleeve and means for preventing said needle bar from rotating in said sleeve when said set-screw is released.

7. A sewing machine including in combination, a work support, a feeding mechanism, a needle, a needle bar carrying said needle, said needle bar being located in a line forming an obtuse angle to the plane of the work support, an oscillating arm for reciprocating said needle bar, a sleeve surrounding the needle bar, a link connecting said sleeve to said arm, a set-screw for rigidly and detachably connecting the needle bar to said sleeve, said sleeve having a slot therein extending lengthwise of the needle bar, and a screw threaded into the needle bar and having a shank located in the slot for preventing the needle bar from turning when released from connection with the sleeve.

8. A sewing machine including in combination, a work support, a feeding mechanism, an overhanging arm, a shaft disposed in a horizontal plane and at a slight angle to the plane of the overhanging arm, a bracket secured to said overhanging arm and having bearings for said shaft, said bracket having bearings for a needle bar, a needle bar located in said bearings and reciprocating in a line at an obtuse angle to the plane of the work support, and means oscillated by said shaft for reciprocating said needle bar.

9. A sewing machine including in combination, a work support, a feeding mechanism, an overhanging arm, a shaft disposed in a horizontal plane and at a slight angle to the plane of the overhanging arm, a bracket secured to said overhanging arm and having bearings for said shaft, said bracket having bearings for a needle bar, a needle bar located in said bearings and reciprocating in a line at an obtuse angle to the plane of the work support, a forwardly projecting arm rigidly connected to said shaft, and means connecting said arm to said needle bar.
10. A sewing machine including in combination, a work support, a feeding mechanism, an overhanging arm, a shaft disposed in a horizontal plane and at a slight angle to the plane of the overhanging arm, a bracket secured to said overhanging arm and having bearings for said shaft, said bracket having bearings for a needle bar, a needle bar located in said bearings and reciprocating in a line at an obtuse angle to the plane of the work support, a forwardly projecting arm rigidly connected to said shaft, and means connecting said arm to said needle bar.
11. A sewing machine including in combination, a work support, a feeding mechanism, an overhanging arm, a shaft disposed in a horizontal plane and at a slight angle to the plane of the overhanging arm, a bracket secured to said overhanging arm and having bearings for said shaft, said bracket having bearings for a needle bar, a needle bar located in said bearings and reciprocating in a line at an obtuse angle to the plane of the work support, a forwardly projecting arm rigidly connected to said shaft, and means connecting said arm to said needle bar, a looper cooperating with said needle beneath the work support, means for moving the looper laterally for imparting a needle avoiding movement thereto, an arm projecting rearwardly from said shaft, and devices connecting said rearwardly projecting arm with said looper for moving the same into and out of the needle loop.
12. A sewing machine including in combination, a work support, a feeding mechanism, an overhanging arm, a shaft disposed in a horizontal plane and at a slight angle to the plane of the overhanging arm, a bracket secured to said overhanging arm and having bearings for said shaft, said bracket having bearings for a needle bar, a needle bar located in said bearings and reciprocating in a line at an obtuse angle to the plane of the work support, a forwardly projecting arm rigidly connected to said shaft, and means connecting said arm to said needle bar, a looper cooperating with said needle beneath the work support, means for moving the looper laterally for imparting a needle avoiding movement thereto, an arm projecting rearwardly from said shaft, and devices connecting said rearwardly projecting arm with said looper for moving the same into and out of the needle loop, said devices including a rock lever fulcrumed on said bracket.
13. A sewing machine including in combination, a work support, a feeding mechanism, a needle, a needle bar carrying said needle and located in a line at an obtuse angle to the plane of the work support, spaced upper and lower bearings for said needle bar, said upper bearing being extended so as to form a housing for the upper end of said needle bar during its reciprocation and thus protect the operator from being accidentally struck thereby, said housing having slots formed therein, said needle bar having an opening in line with said slots whereby the needle thread may be controlled by the upper end of the needle bar.
14. A sewing machine including in combination, a work support, a feeding mechanism, a needle, a needle bar carrying said needle and located in a line at an obtuse angle to the plane of the work support, spaced upper and lower bearings for said needle bar, said upper bearing being extended so as to form a housing for the upper end of said needle bar during its reciprocation, said upper bearing having slots at the forward and rear sides thereof, and a tube carried by the needle bar and projecting from said slots and adapted to receive the needle thread.
15. A sewing machine including in combination, a work support, a feeding mechanism, a needle, a needle bar carrying said needle, a folder having a folding scroll extending about the path of the needle for guiding the binding strip and folding the upper edge portion thereof about the path of the needle, said needle bar being tapered at the lower end thereof whereby the body fabric may be guided well up in the folder without requiring the undue enlargement of the folder.
- In testimony whereof, I affix my signature.
- ROBERT R. HUGHES, JR.
